UNITED STATES PATENT OFFICE.

EDGAR A. HUMPHREY, OF COLUMBUS, PENNSYLVANIA.

WRENCH.

SPECIFICATION forming part of Letters Patent No. 514,752, dated February 13, 1894.

Application filed December 1, 1892. Serial No. 453,772. (No model.)

To all whom it may concern:

Be it known that I, EDGAR A. HUMPHREY, a citizen of the United States of America, residing at Columbus, in the county of Warren, 5 and State of Pennsylvania, have invented certain new and useful Improvements in Wrenches; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to improvements in wrenches, the object of the same being to provide means for forcing the movable jaw of the wrench against the stationary jaw after said movable jaw has been adjusted by the 20 adjusting-nut which engages with the shank to which the stationary jaw is secured and the invention consists in the construction and combination of the parts, as will be hereinafter fully set forth, and particularly pointed out 25 in the claim.

In the accompanying drawings, forming part of this specification: Figure 1 is a side elevation showing, in full lines, the jaws clasping an object and in dotted lines as released 30 therefrom. Fig. 2 is a sectional view on the line $x-x$ of Fig. 1.

A designates the stationary jaw to which the shank A' is rigidly attached, said shank passing through the handle to which it is attached by a nut as shown. The stationary jaw is provided on one side of the shank with a flat face a adapted to engage a nut, while on the other side of the shank the jaw is extended and provided with a curved face a' 35 having dove-tailed recesses in which are secured steel bits for grasping a pipe or tube. The clamping faces of the movable jaws are constructed similar to those of the stationary jaw, and by providing these faces the wrench 40 can be used upon either a nut or pipe.

45 The movable jaw, B, is provided centrally with an aperture through which the shank passes, and on one side of said jaw are formed ears b between which is pivoted a lever C, and 50 said lever is connected to a movable slide D

by means of a short link E. The slide engages with the adjusting-nut F, said nut having an aperture threaded to engage with the threads on the shank of the wrench. The link E is bifurcated at its end which is pivoted to the lever, and at its other end is a projecting portion adjacent to which is formed shoulders which are adapted to bear upon the slide D, and the lever is so constructed that when the free end thereof is moved toward 55 the shank or handle of the wrench to its fullest extent it will bear upon the projection d , and when in this position the pin which connects the link with the lever will be located on the inside of a line connecting the pivot 60 pin in the jaw and the one in the slide; thus locking the lever. The shank A' is provided with flat sides which will prevent the jaw B turning thereon, and the movable slide D is apertured to engage with the flat sides of the 65 shank so that it is kept in line with the jaw B. The nut F has a portion which is embraced by the slide D, so that when the nut is turned the slide will be adjusted upon the shank and will carry with it the movable jaw. 70 The lower end of the movable jaw is provided with a flat face, and the face of the slide is similarly shaped so that when the lever is thrown outwardly, as shown in dotted lines, the slide D and jaw B will bear against 75 each other, and they are usually placed in this position when it is desired to make a great range of adjustment, as the jaw is then not liable to clamp upon the shank. With this construction I may dispense with extra 80 slides or guides.

By this device the movable jaw can be adjusted to the proper distance to grasp a nut or a pipe, and when it is desired to release the wrench it is only necessary to move the 90 lever away from the shank or handle; or if desired the adjustment can be made and the lever employed for forcing the movable jaw toward the stationary jaw and upon the object to be grasped.

I am aware that it has been proposed to provide a wrench with a movable slide which can be adjusted upon the shank, the slide carrying a toggle which is connected with a lever, said lever also providing means for con- 95 100

necting the movable jaw to the or toggle slide, and I do not therefore claim such construction broadly; but

What I do claim as new, and desire to secure by Letters Patent, is—

A combined pipe and nut wrench, consisting of a handle bar having at one end jaws which extend on opposite sides of the handle-bar, a portion of the handle-bar having 10 segmental screw-threads, a yoke-frame D which is adapted to engage with a nut F, the yoke-frame having projecting portions between which is pivoted a link the upper end of which is bifurcated, a sliding-jaw B having 15 a face similar to the face of the jaw A and a recess in which a lever C is pivoted,

said lever having a projecting portion to which the bifurcated end of the link E is pivoted, the parts being organized substantially as shown, whereby when the lever is moved 20 to its full limit toward the handle-bar the central pivot which connects the lever to the link will be out of line with the pivots which are in the yoke and sliding-jaw, for the purpose set forth.

In testimony whereof I affix my signature in presence of two witnesses.
